UNITED STATES PATENT OFFICE.

JOHN P. GALLAGHER, OF JERSEY CITY, NEW JERSEY, ASSIGNOR TO MAGOR CAR CORPORATION, OF NEW YORK, N. Y., A CORPORATION OF DELAWARE.

CENTER-SILL REINFORCEMENT.

Application filed March 12, 1924. Serial No. 698,738.

To all whom it may concern:

Be it known that I, JOHN P. GALLAGHER, a citizen of the United States, and resident of Jersey City, in the county of Hudson and State of New Jersey, have invented certain new and useful Improvements in Center-Sill Reinforcements, of which the following is a specification.

The invention relates in general to an improved form of car center sill construction for use in connection with freight, passenger and other forms of cars when formed of metal and/or wood, and the invention specifically relates to a metallic reenforcement for car underframes which have their center and other sills formed wholly or in part of wood.

This application constitutes a development of the disclosure in my copending application for combined draft arm and center sill reenforcement, Serial No. 595,461, filed October 18, 1922, and the present disclosure is to be regarded as another embodiment of the inventive features disclosed and claimed in this pending application.

In the form of the invention herein selected for specific discussion reference will be made to the metallic reenforcement for the wooden center sills found on certain makes of freight cars now in general use. The underframes of these cars are usually not of sufficient strength to resist either the load imposed thereon nor the pulling and buffing shocks incidental to present service conditions. This weakness of construction is noted throughout the entire center sills and is caused principally by the fact that within recent years the hauling capacity of freight locomotives and cars has been practically doubled. Further, in accordance with present American Railway Association requirements new freight cars are built with steel center sills containing not less than thirty square inches sectional area of metal between rear draft lugs. Freight cars with both wood and steel center sills are placed in trains indiscriminately so that the cars with wooden center sills are subjected to the same shocks as those having heavy modern steel center sills. In consequence of the more powerful locomotives and the more massive cars used and the increased tonnage hauled in each train, the pulling and buffing shocks incidental to the starting, propelling and

stopping of the trains have likewise been proportionately increased. In starting and propelling the present day train the increased draw bar pull caused by the increased tonnage and number of cars hauled in each train proportionately increases the pulling shocks which results in increased direct tension in the two center sills between front draft lugs, and likewise in stopping the present day train the increased momentum caused by the increased tonnage and number of cars hauled in each train proportionately increases the buffing shocks which result in increased compression of the two center sills between rear draft lugs. It is evident from the increasing number of failures in service of cars equipped with wooden center sills that the tension and compression above described are consequently greater than was expected by the designers of these cars. Therefore it is a general purpose of this invention to provide a means for reenforcing these wooden center sills preferably throughout their length between end sills, or at least where increased strength is desired in a manner sufficient to meet the requirements of present day service conditions.

Attempts have been made to reenforce these wooden sills by providing a fabricated metal channel beam construction which is secured to the wooden sills for the purpose of providing additional strength to the wooden car underframe. This reenforcement has heretofore been formed of standard forms of rolled channel iron, heavy H-beams and angle forms secured together by flat plates riveted through the flanges of the beams and forms. The use of these commercial forms is apparently regarded as necessary to give sufficient cross-section of material so as to provide the necessary reenforcement and it has been considered that the forms should have a greater cross-sectional area than is theoretically necessary in order to compensate for the weakening effect of the several rows of holes provided for the fastening rivets used to secure the parts. In the reconstruction of used freight cars in the manner herein suggested, it is vitally necessary that the cost of strengthening the underframe be reduced to the lowest possible figure, and accordingly any saving of material, however slight, and any elimination of labor or ma-

ching is of great importance from a commercial standpoint.

Accordingly, the primary object of the present invention, as was the primary object 5 of the invention in the above identified application, is to provide a simplified form of reenforcement for wooden car underframes which will feature a minimizing in the amount of material used, as well as the cost 10 necessary to fabricate the reenforcing structure; which will eliminate parts heretofore regarded as necessary in such constructions; which will reduce the amount of labor necessary to mount the reenforcement in position 15 in the underframe and at the same time which will provide a type of reenforcement adequate to the modern requirements of structural strength in such circumstances.

The present disclosure resembles the disclosure 20 in the above identified application in that the reenforcement at each end of the car is in the form of a one-piece pressing, the central portion of which is formed into a U-shaped channel fitting between the center sills to be reenforced, and provided with outstanding flanges which act as gusset plates and the parts of which between the end sill and the bolster and between the center sill and bolster act as diagonal strain 25 transmitting braces.

Incidental to the general object of providing a reenforcement which will meet the requirements of the Car Builders Association and at the same time minimize in the amount 35 of material used, the invention features a reenforcement which will be formed in part by the intermediate and other sills already in the car underframe structures to be reenforced and in this way utilize the intermediate sills as part of the center sill re-enforcement.

Broadly this phase of the invention is attained by tying the portion of the intermediate sills at the points where they cross 45 the bolster, to the center sill reenforcement and specifically to the gusset plates forming elements of this reenforcement.

In the previous application the portion of the reenforcement between the end sill and 50 the bolster and between the center sill and bolster were described as strain braces. In the present disclosure, additional diagonal strain transmitting braces are featured and are designed not only to resist buckling of 55 the gusset plates but are also designed to provide the braces as vertically disposed elements coacting with the gusset plates to form angle braces capable of resisting strains both horizontally and vertically directed.

Another object of the invention is to provide a form of car end reenforcement particularly designed for use in connection with 60 wooden underframes and which will act independently of the bolster to secure the center and intermediate sills against spreading.

or other buckling action at the bolster and which will act additionally to secure the reinforced sills to the bolster.

Broadly this phase of the invention is attained by providing upstanding elements 70 either as integral parts with the reenforcing pressing, herein featured, or as separable parts such as clips, brackets, and the latter of which may also act as stringer brackets. Further featuring the desideratum to obtain maximum strength with the least amount of material used, the present disclosure features the corrugating of certain 75 of these horizontally disposed strain transmitting members, such as the gusset plate 80 and the horizontal flange fitting between the center sills, and the disposition of the fastening bolts in such way as to take advantage of their resistance to shearing action and in this way insure a positive securing of the 85 reenforcing parts to both the sills and bolsters with the least number of rivets or bolts and in a way to minimize the weakening effect which characterizes a structure having a multiplicity of bolt holes.

Various other objects and advantages of the invention will be in part obvious from an inspection of the accompanying drawings and in part will be more fully set forth in the following particular description of one 95 form of mechanism embodying my invention, and the invention also consists in certain new and novel features of construction and combination of parts hereinafter set forth and claimed.

In the accompanying drawings:

Figure 1 is a plan view adjacent one end 100 of a wooden car underframe equipped with a preferred embodiment of the invention and with parts broken away to show details of construction.

Figure 2 is a perspective view of one of the end units forming part of the complete reenforcement partially shown in plan in Fig. 1, together with a part of the associated 110 central unit.

Figure 3 is a longitudinal sectional view taken in the longitudinal medial plane of the car, on the line 3—3 of Figure 1 and looking in the direction indicated by the 115 arrows; and

Figure 4 is a transverse sectional view adjacent the bolster taken on the line 4—4 of Figure 1 looking in the direction indicated by the arrows.

In the following description and in the claims, parts will be identified by specific names for convenience of expression but they are intended to be as generic in their application to similar parts as the art will 125 permit.

In the drawings there is shown a wooden car underframe formed of longitudinally extending members, comprising a pair of transversely spaced apart wooden center 130

sills 10 and 11, side sills 12 and 13, and intermediate sills 14 and 15; and transversely extending members including one of the end sills 16 and the adjacent bolster 17. It is understood that the structure shown in Figure 1 is duplicated at the opposite end of the car. There is also disposed in outline certain other structural features of the car, including a buffer block 18, and one of a pair of draft sills 20 which draft sills underlap the center sills and extend from the bolster to the front of the guard plate as is usual in such constructions.

It is understood that this showing is intended to represent conventional structures and to disclose a type of wooden underframe which is to be reenforced by the metallic construction particularly forming the subject-matter of this application.

20 In the form herein illustrated the center sill reenforcement comprises three major and two minor units formed of metal plate pressings. Of the major pressings there is intended to be used two end members each 25 extending from one of the end sills past the adjacent bolster, and a connecting member disposed between the end members and fastened at each end to the end members by means of tie plates which constitute the two 30 minor units and are preferably pressings.

Referring to either of the end members, 21 in Fig. 2, there is illustrated a single metal plate pressing having a length sufficient to extend from the end sill to the 35 bolster and preferably across the bolster for a distance equal to or less than the distance from the bolster to the end sill. In the preferred form shown in Figure 1 the pressing is of a length to extend towards the center 40 of the car from the bolster a distance approximately more than one-half of the distance between end sill and bolster. The central portion of the pressing is bent longitudinally into a channel 22, inverted U-shaped in cross-section and of a size to fit 45 between the inner faces of the center sills and acting to form a thrust beam at the adjacent end of the car underframe. This beam includes a pair of vertically disposed 50 webs 24, a top flange 25 and outstanding bottom flanges 26 which project integrally from the lower edges of each of the webs 24 and coact therewith to provide right angle seats for the wooden center sills 10 and 11.

55 The flanges 26 are extended on each side beyond the outer faces of the adjacent center sills to provide horizontally disposed plates 27. Each plate is of maximum width along the bolster, and in the form of the invention disclosed in Figure 1 extends at least to the adjacent intermediate sill 14 or 15. The plate is of gradually reduced width in both directions from the bolster and forms between the bolster and the adjacent end sill 60 a triangular shaped plate 28 which coacts

with the adjacent upstanding web 24 to form an angle pressing which in addition to providing a seat for the wooden sill will function as a diagonal strain transmitting brace to distribute shocks received at the center of the end sill and to convey the same to the portions of the bolster to the outside of the center sills.

In another aspect of the disclosure it may be considered that the narrow flange 26 on each side of the center together with the portion 28 of the extension and without the web 24 will be of sufficient strength to constitute a strain brace. The general effect of the construction as thus far described will be to 70 effect a transference and distribution of shocks at the center of the end sill in direct lines to the central portion of the bolster and along outwardly divergent lines to the portions of the bolster outside of the center sill construction. The portion of the flanges 28 which extend horizontally beyond the center sills are fastened to the bolster by means of rivets 29 and in this way there is provided a plate which functions as the 75 usual gusset plate between the center sill construction and the bolster.

The central unit 30 connecting the end pressings 21 resembles the end pressings in outline and dimension, except that it is not provided with the gusset plate forming extensions 27. This part of the construction is simply a one-piece channel shaped member, preferably a pressing, inverted U-shaped in cross section and provided with outstanding flanges 31. However, this part as well as the end pressings 21 may obviously be formed of two Z members riveted together. The ends of the central pressing are secured to the adjacent end pressings by means of 80 tie plates 32 which extend across the joints between the units and are fastened by rivets 33. In the present disclosure this tie plate corresponds in cross section to the central member, except that it is of correspondingly 85 smaller size so as to fit in the trough or channels of the members to which they are attached.

Where the question of economy in reenforcements is vital the central pressing may 90 be reduced in the amount of material used; may have some of its parts omitted; or may be omitted entirely. In this latter case dependence is placed upon the unreinforced wooden center sills to provide the necessary 95 structure parts at the center of the underframe.

The parts of the reenforcement are secured to the center sills by vertically disposed bolts 34 and horizontally disposed bolts 35.

The construction as thus far described has its analogous parts correspondingly numbered in the above identified application, and it is intended that the claims 100

in said pending application shall be read sufficiently broad to cover the modifications disclosed in this application.

In the present disclosure the reenforcing pressing is continued laterally behind the showing in the previous disclosure so as to include the intermediate sills 14 and 15 as a part of the same and thus add the cross-section of material in the intermediate sills to 10 make up the necessary cross-section of material in such structures required by the Master Car Builders. This may be attained either by the use of an integral angled extension 38 from the gusset plate 28 as shown at 15 the right of Figures 1, 2 and 4, or it may be a separate angle piece 39 riveted to the gusset plate at the point where it laps the bolster as shown at the left side of the center sills in Figures 1 and 4. In either case the extension is secured to the intermediate sills by means of horizontally disposed bolts 40. In the showing of the form of intermediate sills reinforcements at 38 it is disclosed as 20 comprising an inverted U-shaped pressing 25 designed to conform in configuration to and fit across the top of the intermediate sills and are fastened thereto by means of vertically extending bolts 41. It is obvious that this sill overlapping form of engagement 30 with the intermediate sills may be a separate piece from the gusset plates and secured thereto as suggested with reference to the angle piece shown at 39.

For the purpose of preventing outward 35 spreading of the intermediate sills where the reenforcement simply extends upward on one side of the intermediate sill, as is the case in the showing at 39, a separate angle 42 is positioned on the outside of the intermediate sill. Such an extension from the reenforcement provided by the pressing 21, additionally acts as a clip for receiving the adjacent ends of the bolts 40. The lower, outer flange of the intermediate sill reenforcement, in either the form shown at 38 or 45 42 is secured to the bolster by vertical bolt 43. It is obvious that the intermediate sills may be separately reenforced and secured to the center sill reenforcement following any approved practice; the intent of 50 this disclosure being principally to provide a center sill reenforcement which will include intermediate and other sills and which may, if desired, be extended even to include 55 the side sills.

In order to prevent spreading of the center sills, stops 44 preferably in the form of angle brackets, are positioned in the angles between the outer face of each center sill and 60 the gusset plate with the vertical flange thereof secured by the horizontal bolts 35 and the horizontal bottom flange secured by bolts 45. As these brackets are in the position where the stringers usually extend it is suggested that the usual stringer bracket be

utilized as a stop member to prevent spreading of the center sills and to add material to the center sill reenforcement without necessity of providing a member particularly for this purpose. Accordingly, in the present disclosure the brackets 44 are illustrated as stringer brackets and are shown supporting stringers 46.

In the prior disclosure the gusset plates were shown simply as flat plates. In the present disclosure these plates are strengthened transversely of their planes in two ways, first by corrugating the same as indicated at 47 and secondly by downturning the outer edges to form vertically disposed flanges 48. The corrugations, of course, tend to prevent buckling of the plate and add materially to its resistance to distorting strains without materially adding to the amount of material present in the alternative form of flat plates. The down-turned flange 48 may be regarded as a vertically disposed strain transmitting brace which extends from the end sills to the bolster on opposite sides of the center sill and which 90 extends from the portion of the center sill beyond the bolster forwardly and outwardly to the bolster so as to transmit to the bolster strains received from the opposite end of the car underframe. 95

The downturned flange may be regarded when considered with the horizontal disposed plate 28 as an angle bar which also acts as a strain transmitting member. Further the horizontal web 24, plate 28, and flange 48 may be regarded as a particularly efficient form of Z-shaped strain transmitting brace. In any case the braces extend on opposite sides of the medial plane of the car and provide an extremely rugged form of 105 strain transmitting structure for transferring strains not only to the bolster but also to the intermediate sills.

It is herein suggested that the top flange 110 25 be corrugated as indicated at 49 and these corrugations may extend for the entire length of the car underframe by corrugating the top flange 50 of the central unit 30. It is also suggested that the outstanding flanges 31 have their outer edges downturned as 115 shown at 51 which acts to strengthen the flanges 31 and constitute in effect a continuation of the flanges 48 at opposite ends of the car underframe.

A filler block 52 is positioned between the 120 webs 24 and is secured to the end sill 16 by means of bolts 37 passed therethrough and through the buffer block 18.

By means of a reenforcing construction such as is herein disclosed it is possible to 125 provide the old wooden car underframe with sufficient cross-section of reenforcement to meet modern requirements and at the same time to attain this result while featuring economy in the amount of metal used and 130

economy in the cost of constructing the re-enforcement as well as the cost of installing the same in place.

It is simply necessary to stamp the different reenforcements to the desired dimensions to fit any particular set of car underframe, bolt the same in position through bolt holes many of which are already in the structure to be reenforced and the others of which can be easily formed.

Certain of the wooden structural parts which have heretofore been ignored in estimating the strength of the center sill construction are now brought into the figuring of the strength of the underframe at the bolster at the draft lugs, and all of the associated parts are tied together so as to mutually reenforce and brace each other and thus form a rugged part wood and part metal underframe which meets modern requirements of structural strength.

Having thus described my invention, I claim:

1. In a car underframe, the combination of a pair of center sills, a pair of intermediate sills, a pair of side sills, an end sill and a bolster, of a reenforcement comprising a structural unit having a central part fitted between the center sills to reenforce the same, having outstanding flanges constituting gusset plates on each side of the center sill, overlapping the bolster, and extending longitudinally therefrom to the end sill to form strain braces, and means for tying the gusset plates to the vertical sides of the intermediate sills whereby the unit acts as a spacing member for securing the intermediate sills in fixed relation to the center sills and whereby both the center and intermediate sills are united and mutually reenforced.

2. In a device of the class described, the combination with a car underframe, complete per se, and including a pair of wooden center sills and a pair of intermediate sills, said sills collectively having a sectional area of material of a strength less than that equal to thirty square inches of metal, of a structural metal unit constituting a reenforcement secured to both the pair of center sills and to the pair of intermediate sills, said metal reenforcement having a sectional area less than thirty square inches and coating with the sills to provide a sectional area at least equal to thirty square inches of the metal.

3. In a car underframe, the combination with a center sill, and intermediate sills on opposite sides thereof, of a single pressing fashioned at its center to fit the center sill and constitute a metal reenforcement for the same, said pressing including horizontally extending flanges outstanding laterally from said center sill reenforcing part and means for securing said flanges to the intermediate sills whereby said pressing acts as a reen-

forcement for the center and intermediate sills and also acts as a means for tying the intermediate sills to the center sill and holding the same against collapse.

4. In a car underframe, the combination with a center sill, intermediate sills, and a bolster, of a single pressing including gusset plates overlapping the bolster, on opposite sides of the center sill, said pressing provided centrally thereof with a vertically extending portion constituting a metal reenforcement for the center sill and means including vertically extending flanges at the outer edges of the gusset plates for securing the same to the intermediate sills.

5. In a car underframe, the combination with a center sill, intermediate sills and a bolster, of a single pressing including gusset plates overlapping the bolster on opposite sides of the center sill, said pressing provided centrally thereof with a vertically extending portion constituting a metal reenforcement for the center sill and provided with means for securing the pressing to the intermediate sills.

6. In a car underframe, the combination with a center sill, other sills on opposite sides of the same and a bolster, of a single structural unit secured to the bolster and provided with means for tying the sills in their preset relative position and provided with parts for reenforcing the center sills.

7. In a car underframe, the combination with a center sill, other sills on opposite sides of the same, and a bolster, of a single structural unit secured to the bolster and provided with means for tying the sills in their preset relative position and provided with parts for reenforcing the center sills and means secured to the unit for reenforcing said other sills.

8. In a car underframe, the combination of a wooden structure including a pair of center sills and a pair of outer sills, of a metal reenforcement provided centrally thereof with means for reenforcing the center sills horizontally disposed, outstanding flanges constituting combined gusset plates and strain transmitting braces and outer sill-reenforcing means at the lateral edges of said flanges.

9. In a car underframe, the combination with a pair of center sills, a pair of intermediate sills, cooperatively associated to form a car underframe and a bolster, of a structural unit provided with means fitting between and reenforcing the center sills and with other means engaging the intermediate sills to reinforce the same and to tie the intermediate sills to the center sills.

10. In a device of the class described, the combination with a car underframe complete per se and including wooden center sills and other sills, which collectively have a sectional area of material less than a pre-

- scribed strength of sectional area, of a metal reenforcement for both the center sills and said other sills, said metal reenforcement having a sectional area of material sufficient 5 to supplement said wooden center and other sills and coating therewith to provide the prescribed strength of sectional area.
11. In a car underframe, the combination of a wooden structure including a pair of center sills and a pair of outer sills, of a metal reenforcement provided centrally thereof with means for reenforcing the center sills horizontally disposed, outstanding flanges constituting combined gusset plates 10 and strain transmitting braces and outer sill-reenforcing means at the lateral edges of said flanges and bolts for securing said reenforcement to the bolster.
12. In a car underframe, the combination 20 with a bolster, its adjacent end sill and a center sill, of a one-piece pressing bent to form a center sill reenforcement with horizontally outstanding gusset plates on opposite sides thereof and having the lateral 25 edges of said gusset plates turned out of the plane of the plates to form a pair of diagonal strain braces extending from the end sill to the bolster on opposite sides of the reenforced center sill.
13. In a car underframe, the combination 30 with a bolster, its adjacent end sill and a wooden center sill, of a metallic reenforcement for the portion of the wooden center sill between the end sill and bolster and including a horizontally disposed gusset 35 plate projecting laterally from the center sill and having its outer edge extending diagonally from the end sill adjacent the center sill bent to form a vertically disposed 40 flange constituting a diagonal strain brace between the end sill and the bolster.
14. In a car underframe, the combination 45 with a center sill and a bolster, of a center sill reenforcement including an outstanding gusset plate extending longitudinally on opposite sides of the bolster, said gusset plate converging in width from the bolster towards the center side, the outer edge of the gusset plate being bent to form strain transmitting 50 braces extending on one side to the bolster from the part of the center sill adjacent the end sill and extending on the other side of the bolster from the center sill outwardly to the bolster.
15. In a car underframe construction, the 55 combination with a bolster and an end sill, of a structural unit extending from the end sill past the bolster, overlapping and supported by the bolster, said unit including 60 in order outwardly on each side of the medial plane of the car, an inner vertically disposed web, a horizontal web constituting a gusset plate and an outer vertical web, all integrally connected, the parts between the 65 end sill and the bolster constituting strain distributing braces Z-shaped in transverse cross-section.
16. In a car underframe, the combination with center and other sills, a structural unit including a vertically extending part for re-enforcing the center sill and a horizontally extending flange projecting from the bottom of the center sill towards one of said other sills, said flange having a down-turned part acting to lower the center of figure of the vertical part of the unit reenforcing the center sill.
17. A structural reenforcing unit for a car underframe including a gusset plate adapted to underlap the center sill and extend toward another sill, an edge of said plate being down-turned to form a strain brace and the part of the plate adapted to extend across the bolster being up-turned to fit against a side of one of the other sills.
18. In a car underframe, the combination of a center sill to be reenforced and a bolster, of a one-piece pressing constituting a structural unit including a center sill re-enforcing part, a gusset plate and a diagonally extending strain distributing brace at the outer edge of the gusset plate.
19. A structural unit for car underframe comprising a central inverted U-shaped center sill reenforcing part, horizontally extending flanges projecting laterally from said central part and forming gusset plates and the outer edges of said plates being down-turned to form with the gusset plates diagonal strain braces.
20. A structural unit for car underframe comprising a pressing including a central inverted U-shaped center sill reenforcing part, horizontally extending flanges projecting laterally from said central part and the outer edges of said flanges being down-turned.
21. In a car underframe, the combination of a pair of center sills and other sills, of a reenforcement including a U-shaped part fitted between the center sills to reinforce the same, laterally extending flanges underlapping the center sills and having their outer edges upturned to fit against said other sills, and shear bolts for securing said upturned edges to the other sills.
22. In a car underframe, the combination of a pair of center sills, a reenforcement including a part fitted between the sills to prevent relative movement in the direction towards each other, and including outstanding flanges underlapping and projecting beyond the center sills, stop members projecting upwardly from the projecting portions of said flanges and engaging the center sills on the outer sides thereof to prevent relative movement in the opposite direction and stringers carried by said stop members.
23. In a car underframe, the combination of a bolster, a sill, a reenforcement for the

sill underlapping the same and overlapping the bolster, a stringer bracket secured to and projecting upwardly from the reenforcement, constituting a part thereof and engaging one side of the sill to prevent movement of the same in the direction towards said bracket.

24. In a car underframe, the combination with a center sill, an intermediate sill and a bolster, of a reenforcement including a gusset plate extending from the center sill to the intermediate sill and overlapping the bolster, said plate provided with means upstanding therefrom for engaging vertical sides of both the center and intermediate sills to reinforce the same and bolts for securing said means to their associated sills.

25. A reenforcement for a car underframe comprising a gusset plate provided with means for securing the same to the center sill and provided with an angled clip for securing the same to an intermediate sill.

26. A structural reenforcing unit for a car underframe including a gusset plate adapted to underlap the center sill and extend towards another sill, an edge of said plate being down-turned to form a strain brace, and a clip at the outer edge of said plate for securing the same to said other sill, said clip being inverted U-shape and adapted to overlap said other sill.

27. A structural reenforcing unit for a car underframe including a gusset plate adapted to underlap the center sill and extend towards another sill, an edge of said plate being down-turned to form a strain brace and a clip at the outer edge of said plate for securing the same to said other sill.

28. In a car underframe, the combination of a pair of sills, a reenforcement extending between the sills and including a pair of

vertically extending elements, engaging the sills, one for each sill, horizontally extending bolts passing through each sill and its associated reenforcement element, and clips engaging each bolt on the side of the sill opposite the side engaged by its associated element.

29. In a car underframe, the combination of a sill, a reenforcement therefor including a vertically disposed element, a horizontally extending bolt passed through the element and sill, and a clip between the bolt and sill.

30. In a car underframe, a metal reenforcement including a central channel shaped portion with outstanding flanges, the web of the channel shaped portion and said flanges being corrugated.

31. In a car underframe, a sheet metal reenforcement including horizontal and vertically extending elements, the horizontal extending elements being corrugated.

32. In a car underframe, a reenforcement including a horizontally disposed gusset plate, said plate provided with corrugations.

33. A reenforcement for a center sill comprising a pressing including a U-shaped part adapted to be inserted between a pair of center sills and a filler block fitted within said U-shaped part.

34. In a car underframe, the combination of an end sill and a pair of center sills to be reenforced, a metal reenforcement including an inverted U-shaped pressing fitted between the center sills to prevent their collapse and extending inwardly from the end sill and a filler block fitted between the pressing adjacent the end sill.

Signed at New York city in the county of New York and State of New York this 10th day of March A. D. 1924.

JOHN P. GALLAGHER.
